UNITED STATES PATENT OFFICE

2,640,347

KEY CASE

Joseph J. Majeski, Porter, Ind.

Application April 30, 1951, Serial No. 223,707

2 Claims. (Cl. 70—456)

1

This invention relates to a combined flashlight and key container, the open-ended hollow body having a cap providing access to the key attaching means while functioning as means to retain components of the flashlight in proper operative position.

A primary object of the invention is to provide a combination flashlight and key container wherein certain elements cooperate in a novel manner and wherein all the elements cooperate to provide an extremely useful device.

Another object of this invention is to provide a combination article wherein the key accommodating elements are such that keys of different sizes and shapes may be used with the device.

Another object of the invention is to provide a novel latch means for the cover closing the open end of the hollow body of the device.

Still another object of this invention is to provide a highly utilitarian and novel combination dry cell holder and switch which is especially well adapted for devices of this general character.

General objects of the invention include, the provision of means whereby the keys may be conveniently exposed, one at a time, to provide means whereby a considerable number of keys can be conveniently carried in an attractive container of no great bulk, and to provide means whereby a light can be made to shine on the key hole at the instant when the key is being inserted.

A last object to be mentioned specifically is to provide a device of this character which is relatively inexpensive and practicable to manufacture, which is simple, safe and convenient to use, and will give generally efficient and durable service.

With these objects definitely in view, this invention resides in certain novel construction, combination and arrangement of elements and portions as will be hereinafter described in detail in the specification, particularly pointed out in the appended claims, and illustrated in the accompanying drawings which form a material part of this application, and in which:

Figure 1 is a view, in perspective, of the assembled device;

Figure 2 is a vertical longitudinal sectional view, taken substantially on the line 2—2 in Figure 3;

Figure 3 is a horizontal sectional view taken substantially on the line 3—3 in Figure 2;

Figures 4 and 5 are vertical cross sectional views taken on the lines 4—4 and 5—5, respectively, in Figure 2;

2

Figure 6 is a view, in perspective, of the cross-head slide; and

Figure 7 is a view, in perspective, of the combination dry cell holder and switch.

Similar characters of reference designate similar or identical elements and portions throughout the specification and throughout the different views in the drawings.

Referring now to the drawings in detail, this invention includes an elongated hollow body 10, having an open end 12 which is closed by a cap 14. This cap has a flange 16 which slides within the said open end 12, to abut a shoulder 18 formed in the body 10 adjacent to said open end. Small plungers or latch bolts 20 are axially slidably mounted in opposed bores 22 provided in opposite side portions of the flange 16, and recesses 24 are provided in correspondingly positioned parts of the end 12 of the body, so that when said latch bolts 20 are moved outwardly, the cap 14 is held in place. An elongated spring connector 26 has its central portion wound at least once around a cylindrical member 28 mounted for rotative oscillation in a central portion of the cap 14. The outer end of the member 28 is formed with a head 30 having a screw-driver slot therein so that the member 28 can be oscillated to pull the spring connectors 26 and the latch bolts 20 so as to release the cap 14, the resiliency of the spring connectors 26 being depended upon to urge the said latch bolts 20 outwardly into locking position, as indicated in Figure 3. The spring connector 26 is terminally secured to the latch bolts 20 in any suitable manner, as indicated in Figure 4, the particular mode of attachment illustrated comprising the insertion of end portions of the spring connector through transverse bores in the latch bolts 20 and the bending of the extreme ends of the spring connectors as illustrated.

The end of the body 10 remote from the cap 14 is provided with a plurality of transverse parallel slots 32 to admit a plurality of keys 34. A plurality of crosshead slides, generally indicated at 36, in Figure 6, are provided and each slide 36 is provided with an element including a hook 38 to engage a key and a shank 40 extending through a reduced waist portion 42 of the corresponding slide 36. It should be carefully noted that the shank 40, although threaded, is of non-circular shape and the bore provided therefor in the waist portion 42 is of similar non-circular shape, so that relative rotation between these elements is prevented. The enlarged upper and lower portions of the slides 44 and 46 respectively carry the shoes 48 and 50 which slide in channels 56 and 58, respectively, pro-

vided in opposed relation in side walls of the body 10, it being noted that a slot 52 is formed in that side of the slide 36 adjacent to the transverse slots 32, this slot 52 being adapted to receive the corresponding end of a key 34, and it should be further noted that a nut 54 is threaded on the shank 40 so that the hook 38 can be withdrawn in order to hold the key 34 with a portion thereof within the slot 52. Finally, in this connection, the channels 56 should be considered portions of longitudinal slots 62 extending through the corresponding side wall of the body 10 to accommodate the button 60 provided on each slide 36, the button 60 allowing the slide, with the key 34 mounted thereon to be pushed, as indicated at 64 in Figure 1, in one direction so that the corresponding key 34 is exposed at the end of the body 10.

A hollow enlargement or chamber 66 is formed integral with that side wall of the body 10 remote from the side wall having the slots 62 therein, and a small aperture 68 is formed in the end wall of this chamber 66. The chamber 66 accommodates a flashlight, including a small electric lamp 70 inserted in a stepped recess 72 communicating with the aperture 68, the larger portion of this stepped recess accommodating the screw base 74 of a conventional flashlight lamp 70. A dry cell 76 is urged by a spiral spring 75 into engagement with the center contact 77 of the lamp 70, and it will be noted that the cap 14 has a seat 78 formed therein for the spring 75, this spring being compressed between that portion of the cap 14 comprising the seat 78 and the end of the dry cell remote from the lamp 70. In this construction it is important that the dry cell 76 be reasonably rigidly held, and this is accomplished by a portion of the combination dry cell holder and switch indicated generally by the numeral 79 and best illustrated in Figure 7. A sleeve 80 fits snugly upon an intermediate portion of the dry cell 76. The sleeve is secured to an intermediate portion of a plate 82 which is elongated and which extends along the chamber 66, and an offset portion 84 of the plate 82 engages another portion of the dry cell 76. It will be understood that the dry cell has a center terminal 85 contacting the center terminal 76 of the lamp. Furthermore, the body 10 will ordinarily be constructed of non-conductive material and the sleeve 80 is in conductive engagement with the zinc casing of the flashlight dry cell 76. A switch button 86 is rigidly secured by any suitable means to a portion of the plate 82 extending toward the lamp 70, and this switch button extends through an aperture 87 in the chamber 66, so that upon pressure of the thumb or finger applied to the switch button 86 the spring contact 88 is engaged with the screw base 74 of the lamp 70, completing the electrical circuit through the contacts 77 and 85, the lamp 70, the plate 82 and the sleeve 80, so that light from the lamp 70 will shine through the aperture 68.

The operation of this invention will be clearly understood from a consideration of the foregoing description and the mechanical details throughout, taken in connection with the above recited objects and the drawings. Further description would appear to be unnecessary.

It will be understood that minor variations from the disclosed embodiment may be resorted to without departure from the spirit and scope of this invention.

Having described the invention, what is claimed as new is:

1. An elongated hollow body having a closed end with parallel transverse slots therein and an open end opposite to the closed end, a cap comprising a closure for the open end, said body 5 having a first side wall with parallel longitudinal slots therein, the transverse and longitudinal slots being equal in number and arranged so that the axis of each transverse slot is coplanar with the axis of a longitudinal slot, said body 10 including a second side wall opposite said first side wall and having channels parallel to said longitudinal slots, opposing channels comprising enlarged inner portions of said longitudinal slots, crosshead slides operatively mounted in said 15 channels, said slides having reduced waist portions, said waist portions having bores of non-circular cross sectional shape extending therethrough parallel to said longitudinal slots, shanks of corresponding non-circular cross sectional 20 shape non-rotatively extending through said bores, key engaging hooks on the ends of said shanks adjacent said transverse slots, the outer ends of said shanks being threaded, nuts on the threaded ends, buttons on said slides and extending through said longitudinal slots to facilitate 25 manual operation of the slides.
2. An elongated hollow body having a closed end with parallel transverse slots therein and an open end opposite to the closed end, a cap 30 comprising a closure for the open end, said body having a first side wall with parallel longitudinal slots therein, the transverse and longitudinal slots being equal in number and arranged so that the axis of each transverse slot is coplanar 35 with the axis of a longitudinal slot, said body including a second side wall opposite said first side wall and having channels parallel to said longitudinal slots opposing channels comprising enlarged inner portions of said longitudinal slots, crosshead slides operatively mounted in said 40 channels, said slides having reduced waist portions, said waist portions having bores of non-circular cross sectional shape extending therethrough parallel to said longitudinal slots, shanks of corresponding non-circular cross sectional 45 shape non-rotatively extending through said bores, key engaging hooks on the ends of said shanks adjacent said transverse slots, the outer ends of said shanks being threaded, nuts on the threaded ends, buttons on said slides and extending 50 through said longitudinal slots to facilitate manual operation of the slides, said cap including locking means therein detachably securing said cap to said hollow body, said locking means comprising a shaft rotatably mounted in said cap, longitudinal slots and channels opening into said 55 cap, said cap constituting stop for said slides.

JOSEPH J. MAJESKI.
